UNITED STATES PATENT OFFICE

WILFRID S. DYER, OF BATTLE CREEK, MICHIGAN

LEVEL

Application filed March 24, 1932. Serial No. 600,964.

The main objects of this invention are:

First, to provide a level having illuminated spirit tubes.

Second, to provide improved means for supporting a battery and lamp within the body of the level.

Third, to provide an improved switching mechanism for the lighting circuit accessible at one end of the level.

Fourth, to provide an improved level having these desirable features, which is simple in construction, economical to manufacture, and efficient in operation.

Objects relating to details and economies of my invention will appear from the description to follow. The invention is defined and pointed out in the claims.

A structure which is a preferred embodiment of my invention is illustrated in the accompanying drawing, in which:

Fig. 1 is a view in side elevation of a level embodying my invention, a portion of the body being broken away and shown in vertical section.

Fig. 2 is an enlarged end elevation of the level, and

Fig. 3 is an enlarged fragmentary longitudinal section showing the switch and adjacent parts in detail.

Referring to the drawing, numeral 1 indicates a level having a wood stock or body provided with cavities in which are mounted a horizontal spirit tube 2 and a vertical spirit tube 3. The stock has a longitudinal bore or passage 4 opening to the spirit tube cavities. A dry cell battery 5 is disposed in one end of the bore 4 for furnishing current to the electric lamp 6 which is carried by the socket member 7. The lamp 6 is positioned directly under the horizontal spirit tube 2 and in line with the vertical spirit tube 3 at the intersection of the transverse axes of the tubes, so that the tubes are illuminated by the direct rays of the lamp 6.

The socket member 7 is integral with the strap 8 of conducting material, which is disposed in a groove 9 in the bore 4 and has a downturned flange 10 engaging the shoulder 11 of the recess 12 in the end of the stock.

The paper casing on the battery 5 insulates it from the strap 8.

The recess 12 is provided with a countersunk cover plate 13 having an opening 14 for the push button 15 and a slot 16 for the pivot flange 17 on the switch 18. The plate 13 is held in place by the screws 19. The switch 18 is provided with a stud 20 opposite the push button 15 for positioning the outer end of compression spring 21 which is disposed between the switch 18 and the end of the battery 5 to urge the switch to open position and the battery terminal 22 in contact with the lamp terminal 23. The spring also constitutes a conductor connecting the bottom of the battery to the switch.

The lighting circuit is closed by pressing the push button 15 until the switch 18 contacts with the flange 10 of the strap 8, the circuit including battery terminal 22, lamp terminal 23, lamp 6, socket member 7, strap 8, flange 10, switch 18, spring 21, and battery 5. The circuit is normally open, the spring 21 urging the switch 18 away from the flange 10 for this purpose. The pivot arm 17 on the switch 18 coacts with the opening or slot 16 in the plate 13 to hold the switch in position and acts as a fulcrum for the switch when the push button is actuated.

The level is particularly useful in dark places, the spirit tubes being illuminated by merely pressing the push button 15. Furthermore, with my invention wood stock levels now in quite general use may be converted readily into self-illuminating levels. The dry cell may be renewed by merely removing the plate 13.

Heretofore, carpenters and others have used matches to illuminate the spirit tubes in dark places. This practice is dangerous, and is made unnecessary by my invention, the level being used in the conventional manner where the natural visibility is good and in dark places by touching the push button, as pointed out above.

I have illustrated and described my improvements in an embodiment which I have found very practical. I have not attempted to illustrate or describe other embodiments or adaptations, as it is believed this disclosure

sure will enable those skilled in the art to embody or adapt my improvements as may be desired.

Having thus described my invention, what I claim as new and desire to secure by Letters Patent, is:

1. A level having a wood stock provided with an end recess, horizontal and vertical spirit tube cavities, a longitudinal bore opening to said end recess and said cavities, spirit tubes mounted in said cavities, a strap of conducting material disposed longitudinally of said bore and having a lamp receiving socket member at its inner end and a switch contact flange at its outer end engaging the shoulder formed by said end recess, an electric lamp carried by said socket member at the intersection of the transverse axes of said spirit tubes, a dry cell disposed in said bore with a terminal in contact with the corresponding terminal of said lamp, a countersunk cover plate for said recess secured to the end of the stock and having a push button opening and a switch pivot flange receiving opening, a switch having a pivot flange disposed in said last named opening and a raised push button in said first named opening and a spring positioning stud opposite said push button, and a compression spring of conducting material disposed between said switch and the bottom of the battery.
2. A level having a stock of insulating material provided with an end recess, horizontal and vertical spirit tubes, a longitudinal bore opening to said end recess and said spirit tubes, a strap of conducting material disposed in said bore and having a lamp receiving socket member at its inner end and a switch contact at its outer end, an electric lamp carried by said socket member at the intersection of the transverse axes of said spirit tubes, a dry cell disposed in said bore with its central end terminal in contact with the corresponding terminal of said lamp, a cover plate for said recess secured to the end of the stock and having a push button opening and a switch pivot arm receiving opening, a switch having a pivot arm disposed in said last named opening and a raised push button in said first named opening and a spring positioning stud opposite said push button, and a compression spring of conducting material disposed between said switch and the bottom of the battery.
3. A level having a stock provided with an end recess, horizontal and vertical spirit tube cavities, a longitudinal bore opening to said end recess and said cavities, spirit tubes mounted in said cavities, a strap of conducting material disposed in said bore and having a lamp receiving socket member at its inner end and a lateral switch contact at its outer end engaging the bottom of said recess, an electric lamp carried by said socket member at the intersection of the transverse axes of said spirit tubes, a dry cell disposed in said bore with its central end terminal in contact with the corresponding terminal of said lamp, a cover plate for said recess secured to the end of the stock and having a push button opening, a switch disposed in said recess and having a push button in said opening, and a conducting spring disposed between said switch and said battery, the spring acting to support the parts in longitudinal assembled relation.

ber, a dry cell longitudinally disposed in said bore with its central terminal in contact with the corresponding terminal of said lamp, a cover plate for said recess secured to the end of the stock and having a push button opening, a switch having a raised push button in said opening, and a compression spring of conducting material disposed between said switch and the bottom of the battery.

4. A level having a stock provided with an end recess, horizontal and vertical spirit tubes, a longitudinal bore opening to said end recess and said spirit tubes, a strap of conducting material disposed in said bore and having a lamp receiving socket member at its inner end and a switch contact at its outer end, an electric lamp carried by said socket member at the intersection of the transverse axes of said spirit tubes, a dry cell disposed in said bore with its central end terminal in contact with the corresponding terminal of said lamp, a cover plate for said recess secured to the end of the stock and having a push button opening, a switch having a raised push button in said first named opening and a spring positioning stud opposite said push button, and a compression spring of conducting material disposed between said switch and the bottom of the battery.

5. A level having a stock provided with an end recess, horizontal and vertical spirit tubes, a longitudinal bore opening to said spirit tubes, a strap of conducting material disposed in said bore and having a lamp socket member at its inner end and a lateral switch contact at its outer end engaging the bottom of said recess, a lamp in said socket member, a battery disposed in said bore with an end terminal in contact with the corresponding terminal of the lamp, a cover plate for said recess having a push button opening, a switch disposed in said recess and having a push button in said opening, and a conducting spring disposed between said switch and said battery, the spring acting to support the parts in longitudinal assembled relation.

In witness whereof I have hereunto set my hand.

WILFRID S. DYER.
